UNITED STATES PATENT OFFICE.

DALE MARSHALL, OF CHELTENHAM, ENGLAND.

PORTABLE REST FOR CARRYING BOOKS, PAPERS, AND THE LIKE.

1,074,963.

Specification of Letters Patent.

Patented Oct. 7, 1913.

Application filed February 15, 1912. Serial No. 677,880.

To all whom it may concern:

Be it known that I, DALE MARSHALL, residing at Cheltenham, in the county of Gloucester, England, engineer, a subject of the King of Great Britain, have invented new and useful Improvements in and Connected with Portable Rests for Carrying Books, Papers, and the like, of which the following is a specification.

10 My invention relates to portable reading and writing rests which are solely supported on the user's body and principally carried by a cord around the shoulders, and is intended to fold up into a small space to permit of it being carried in the pocket, distinguished and characterized by most parts thereof depending and moving from a common center and folding one over the other.

20 The device of my invention will be more fully described in connection with the accompanying drawings, and will be more particularly set forth in and by the appended claims.

In the drawings:—Figure 1 shows the device in its folded condition. Figs. 2, 3 and 4, are views in front and side elevation showing the manner in which the device is opened out in readiness for use. Figs. 5 and 6, show the device as it would appear 30 in use respectively by a person standing erect or in a prone position. Fig. 7, are enlarged views of three details of the device. Fig. 8, is an enlarged back view in elevation of the central portion of the device. Fig. 9, is also an enlarged view in side elevation of the central part. Figs. 10 and 11, are other forms of the device in elevation.

Like letters of reference indicate similar parts in the several views.

40 In carrying my invention into effect I form a portable and collapsible reading and writing rest as shown in Figs. 1 to 9, by pivoting at one common center P six thin grooved and flanged sheet metal members, 45 A, B, C, D, E, and F, one over the other enabling them to be swiveled and folded one over the other so as to occupy a small space, as shown in Fig. 1. The upper part is formed by connecting the outer extremities 50 of two of the said members, namely, A and B, by means of a cord or a strip J jointed at its center, and in the latter case the said strip is centrally grooved for the combined purpose of stiffening and locking in the extended position, the locking being accomplished by the spring like overlapping of

the jointed ends and lengthwise engagement of the grooves of the one part over and into the grooves of the other. Two others, E and F, of the said members which are of angular formation are used as a ledge for the book and are supported at their outer extremities by being attached to the aforementioned members A and B by jointed strips, cord, or as shown in the present instance by chains K to maintain them in a horizontal position relatively thereto; and as denoted in Figs. 4, 5 and 6 I use the two remaining members C and D when splayed apart as struts or a fulcrum to assist in supporting the aforementioned members (which form the upper part of the device) away from the user's body, while the top portion already described is held in semisuspension by a cord H or the like passing around the user's body, under arm pits or over shoulders as denoted in Fig. 6, the end of which cord is attached to the outer and upper extremities of the members A and B. In combination therewith the one end of the 80 said suspending cord H is fixed in a reel R upon which it may be wound both for convenience and to serve as a means for adjusting the position of rest to suit user's sight while the other end has a temporary means of attachment provided by being passed through a slot V made flatwise in the member B and into a round hole formed at the slot's inner end and its withdrawal through the hole is prevented by a knot made at the 85 cord's extremity, which construction, while permitting of the cord's easy attachment, prevents its accidental detachment. To determine and maintain the splayed position of the struts C and D I provide a stop S 90 (see Fig. 8 which gives an enlarged view of the part in question) the stop consisting of an end portion S of the member A which extends below the central pivot P against which one side of the inner strut C abuts when swiveled around in the act of opening, and I also provide a tongue or turned down portion X at that part of the strut D nearest to the central pivot so as to engage shoulders formed by cutting away the metal at 95 U in the other co-acting under strut C.

For the purpose of convenience and holding down the pages of a book placed on the rest, on each of the members E and F forming the ledge I provide spring wire clips 100 made in two parts, the coiled end of the one part W being fixed in a circular recess

O and secured by its end Z passing through the ledge and being turned up and over its edge; the second portion Y is hinged to its outer end, so that while it may be turned up 5 at right angles to the former and clip the pages it will, when folded, lie snugly within the said ledges E and F.

As a modification I may also form the device as an extending lattice (see Fig. 10) 10 whereby the user can adapt the width to requirements, and in which form the struts C and D are made as part of the lattice, and as in the former a ledge for the book is formed of two angular strips E and F which 15 are supported on and secured to each other at their inner ends by a pivot P, and to the framing by secondary pivot P¹, while their outer ends are suitably supported by jointed members or chains K fixed to the lattice 20 frame, and as in the former the device is principally supported by a cord attached to its upper extremities, and passing around the upper part of the user. And as a further modification I may form the device of 25 telescopic tubes or rods (as shown in Fig. 11) in which case the struts C and D may be extensions of the upper splayed members A and B and the cord reel R may be formed endwise on one of the members A and B 30 and as in the previous cases, the latter members are connected by either jointed members or a cord J and the ledges E and F supported centrally by a pivot, and their outer ends in a similar manner as heretofore 35 described, while the supporting cord H is also attached to its upper extremities.

What I claim is:—

1. The combination, in a folding writing or reading rest to be supported and carried 40 by the user, with several strips pivoted at a common center, of means for locking two of the strips in extended position, of means for attaching at the outer extremities of these two strips a cord to be carried over 45 the user's shoulders, of means for connecting to the said two strips other two strips departing from the common center and angular in form to constitute a ledge, and of 50 two struts pivoted at the common center and splayed apart to be rested against the user's body, substantially as described and for the purpose specified.

2. The combination, in a folding writing or reading rest to be supported and carried 55 by the user, with several strips pivoted at a common center, of means for locking two of the strips in extended position, of means for attaching at the outer extremities of these two strips a cord to be carried over 60 the user's shoulders, of means for connecting to the said two strips other two strips departing from the common center and angular in form to constitute a ledge, of two

struts pivoted at the common center and splayed apart to be rested against the user's 65 body, and of means formed by bending of parts of the strips and the struts about a right angle for determining the swiveling direction and securing the struts in the position of use, substantially as described and 70 for the purpose specified.

3. The combination, in a folding writing or reading rest to be supported and carried by the user, with several strips pivoted at a common center, of means for locking two 75 of the strips in extended position, of a reel on the end of one of these two strips, of a slot terminating in a round hole on the end of the other of these two strips, of a cord fixed at one end on the reel and provided 80 at the other end with a knot to be introduced in the slot and hole, of means for connecting to the said two strips other two strips departing from the common center and angular in form to constitute a ledge, and of 85 two struts pivoted at the common center and splayed apart to be rested against the user's body, substantially as described and for the purpose specified.

4. The combination, in a folding writing 90 or reading rest to be supported and carried by the user, with several strips pivoted at a common center, of means for locking two of the strips in extended position, of telescopic extensible parts on these two 95 strips, of means for attaching at the outer extremities of these two strips a cord to be carried over the user's shoulders, of means for connecting to the said two strips other two strips departing from the common center and angular in form to constitute a ledge, and of two struts pivoted at the common center and splayed apart to be rested against the user's 100 body, substantially as described and for the purpose specified.

5. The combination, in a folding writing or reading rest to be supported and carried by the user, with several strips pivoted at a common center, of means for stiffening and locking two of the strips in extended position, of means for attaching at the outer extremities of these two strips a cord to be carried over the user's shoulders, of means for connecting to the said two strips other two strips departing from the common center and angular in form to constitute a ledge, and of two struts pivoted at the common center and splayed apart to be rested against the user's body, substantially as described and for the purpose specified.

In testimony whereof I affix my signature in presence of two witnesses.

DALE MARSHALL.
